UNITED STATES PATENT OFFICE.

JOSEPH LEOPOLD HUBER, OF HAMBURG, GERMANY.

APPARATUS FOR BREAKING ELECTRIC CIRCUITS.

SPECIFICATION forming part of Letters Patent No. 308,261, dated November 18, 1884.

Application filed February 15, 1884. (No model.)

To all whom it may concern:

Be it known that I, JOSEPH LEOPOLD HUBER, a subject of the German Emperor, and a resident of Hamburg, in the German Empire, have invented certain new and useful Improvements in Apparatus for Breaking Electric Circuits, of which the following is a specification.

My invention relates to improvements in apparatus for breaking electric circuits; and the objects of my improvements are, first, to interrupt the electric circuit in a sure and quick manner; and, second, to prevent the formation of sparks. I attain these objects 10 by the mechanism illustrated in the accompanying drawings, in which—

Figure 1 is a top view of a double-circuit breaker. Fig. 2 is a sectional side elevation thereof, and Fig. 3 is a section at the line A.B.

Similar letters refer to similar parts throughout the several views.

a and b are two metal plates connected with the poles of the electric battery. They are affixed to the lower surface of a plate of wood, 25 ebonite, or other insulating material, and by means of the screws c and d, rigidly united with the springs e and f, which rest in their normal position—i. e., when the circuit is broken on the support g of insulating material.

The cam i is pivoted in bearings h h before the support g, and serves to raise the free ends of the springs k and l, which form parts of the circuit, together with the fusible wires n and terminals o and p. The prism or eccentric is 30 kept in any position required by the pressure of the springs k and l, and is manipulated by the hand-lever m.

When the lever m and the prism or eccentric i are in the position illustrated by dotted lines, the springs e and f rest on the springs k and l, thus making contact. Consequently, 40 the current can pass the conduit. To inter-

rupt the circuit the lever m is laid down, which at first requires a certain force, because the springs have to be slightly raised by the edge of the prismatic cam or eccentric until the edge passes the vertical plane of the cam-pivots, when the pressure of the springs throws the cam and lever m down into the recumbent position shown.

As the movement of the springs e and f is very short, being limited by the support g, the contact between them and the springs k and l, which touch only at their overlapping ends, is quickly broken when the cam is lowered.

Having thus fully described my invention with reference to a double-circuit breaker, I do not limit myself to such combination of two pairs of springs, as such pair of springs may be used alone or in combination with two or more equal pairs; but

What I claim as my invention, and desire to secure by Letters Patent, is—

In a circuit-breaker, the combination, with 6 the two overlapping springs connected with opposite ends of a circuit, of a support, g, beneath one of the springs, limiting its downward movement, and the other spring normally tending to move downward out of contact with 7 the first-mentioned spring, and a pivoted cam, i, beneath the last-mentioned spring, having an abrupt shoulder or edge, and a lever-arm, m, connected to said cam, substantially as and for the purpose set forth.

In testimony that I claim the foregoing as my invention I have signed my name, in presence of two witnesses, this 22d day of January, 1884

JOSEPH LEOPOLD HUBER.

Witnesses:

ALEXANDER SPECHT,
DIEDRICH PETERSEN.
